UNITED STATES PATENT OFFICE

GEBHARD JAEGER, OF COLUMBUS, OHIO, ASSIGNOR TO THE JAEGER MACHINE COMPANY, OF COLUMBUS, OHIO, A CORPORATION OF OHIO

PACKING

Application filed May 16, 1928. Serial No. 278,266.

This invention relates to packings for bearings, especially bearings for the agitator shaft of a mixing machine. In such machines there is a constant tendency of the material in the mixing drum to work into the bearings and if the material contains anything of a gritty or corrosive nature, as for example mortar, it injures the parts.

One object of the invention is to provide an improved packing adapted better than those hitherto proposed to resist the tendency of the contents of the drum to enter the bearing. Another object is to provide improved means whereby the packing may be easily examined from time to time and replaced when worn without removing numerous parts. Further objects will appear from the disclosure herein.

The invention is embodied in the example herein shown and described, the features of novelty being finally claimed.

In the accompanying drawing—

Figure 1 illustrates partly in horizontal section a mortar mixing drum equipped with my improved bearings, the drum being broken out vertically and horizontally.

Fig. 2 is an elevation looking at the right hand end of the drum as positioned in Fig. 1, the drum being peripherally broken off.

Fig. 3 is a sectional view on the line III—III Fig. 1.

In the views 10 designates the end fractions of the mixing drum, the ends 11 of which are equipped with perforated trunnions 12 in a packing box 12^a. The character 13 designates the shaft of the agitator that carries blades (not shown) said shaft extending through the packing box and trunnion as best shown at the right hand side of Fig. 1. In its main details the construction of the bearing and packing is substantially the same at each end of the drum. In such a mixing device the shaft 13 is rotated to effect the mixing of the mortar, the drum being supported by the trunnions to permit the tilting thereof as by means of rack 27 and pinion 28 to discharge the contents thereof when mixed.

The box 12^a forms a packing and lubricating chamber, said box being attached to

said head of the drum by bolts 14. The head of the drum is perforated with a circular opening of the diameter of the shaft and on the shaft next the outer side of the head and within the box is a disk 15 of metal or other suitable material perforated for the passage of the shaft. 55

On the shaft 13 next the disk 15 and within the box is a packing member consisting of a volute coiled strip of fibrous material 16 preferably adapted to absorb lubricant. Beyond the packing 16 and loose on the shaft is a compression device consisting of a presser head 17 having that side next the packing smooth and having fixed to or cast with it at its other side a pair of loops like that shown at 18, the space between the loop and the presser head being narrowed at one end and widened at the other. Said other side of the loop is also provided with pins like that shown at 19. Cooperating with the presser head is a base plate or head 20 formed with tubular posts 21 into which extend the pins 19 and on said tubular posts are coil springs 22 bearing against the presser head. Fixed in the shaft 13 are laterally extending pins 23 projecting into the openings formed by the loops. The presser head is formed with lugs 24, 24, between which a tool—a screw driver for example—can be inserted to turn the whole compression device so that the pins 23 may stand either in the narrow space or in the wide space formed by the loop. When the pins 23 are in the narrow space the compression device is locked from longitudinal movement on the shaft and when so locked the packing 16 can be inserted. When the pins 23 stand in the wide space formed by the loop, as shown in Fig. 1 the presser head is free to move longitudinally as regards the shaft 13 and exert pressure on the packing 16 and therefore make a tight joint to prevent the contents of the drum from working into the packing box and bearing. 85

When by long use the packing becomes so thin as to be no longer serviceable the compression device is turned with a tool as before described but to cause the pins 23, 23, to extend into the narrow space by the loop the old packing can be removed and a new one 100

put in, it being noted that in this turning of the compression member the cam-like form of the loop on the pins has the effect of moving the presser head longitudinally on the shaft 13 and away from the worn packing thereby making room for the insertion of a fresh one.

The packing box 12^a is open at its upper side but is provided with a sheet metal cover 25 secured to the head of the drum by a set screw 26 (see Fig. 2) so as to exclude dirt, dust and other objectionable matters from access to the box and bearing. This cover 25 is, of course, removed from time to time to examine the condition of the packing and to replace a worn out one.

The forms of the parts can be changed without departing from the gist of the invention as claimed.

What I claim is:

1. In combination with a mixing drum, and an agitator shaft extending therethrough, said shaft having a pin therein, a packing case and packing therein around the shaft, a packing compression means in said case including a presser head, a spring for actuating the same and means on said presser head cooperating with said pin of the shaft to hold said presser head in a fixed position and when the presser head is turned on the shaft to release said head to press against the packing.

2. In combination with a mixing drum and an agitator shaft extending therethrough, said shaft having a pin therein, a packing case around the shaft, a packing compression member in said case including a base and a presser head, a spring between the base and the presser head, and means on said presser head cooperating with the pin of the shaft to hold said presser head in a fixed position and when the presser head is turned on the shaft to release said head to press against the packing.

3. In combination with a mixing drum and an agitator shaft extending therethrough, said shaft having a pin therein, a packing case around the shaft, a packing compression member in said case including a base and a presser head, means for causing the base and head to turn together on the shaft, a spring between the base and the presser head, and means on said presser head cooperating with the pin of the shaft to hold said presser head in a fixed position and when the presser head is turned on the shaft to release said head to press against the packing.

4. In combination with a mixing drum and an agitator shaft extending therethrough, a packing case around the shaft, a packing compression member in said case including a presser head, a spring to act on said presser head, means on said presser head for holding said head in a fixed position in relation to the packing and means for releasing said presser head for pressure against the pack-

ing upon a turning of the presser head in respect to the shaft.

5. In means of the kind described, a shaft having a pin thereon, a packing compression head on said shaft, a spring for pressing said compression head against the packing, a cam on said compression head cooperating with said pin and adapted, when the head is turned in one direction to latch the head in fixed position in relation to the packing, and, when said head is turned in the opposite direction, to release it for pressure against the packing, a closure for said compression head and packing, said closure having a lateral opening permitting access to the compression head and packing, and a removable cover for said opening.
